UNITED STATES PATENT OFFICE

160,808

METERING PUMP FOR CHEMICAL SOLUTIONS OR THE LIKE

Royal Bartlett Saalfrank, Gulfport, Fla., assignor
to Milton Roy Company, Chestnut Hill, Pa., a
corporation of Pennsylvania

Application October 20, 1949, Serial No. 5,600

Term of patent 14 years

(Cl. D65—1)

To all whom it may concern:

Your petitioner, Royal Bartlett Saalfrank, a citizen of the United States and a resident of Gulfport, in the county of Pinellas, State of Florida, have invented a new, original, and ornamental Design for a Metering Pump for Chemical Solutions or the like, of which the following is a specification, reference being had to the accompanying drawings, forming part thereof.

Figure 1 is a perspective view of the metering pump for chemical solutions or the like embodying my new design;

Figure 2 is a top plan view thereof;

Figure 3 is a side elevational view thereof. The other side, not shown, is substantially the same;

Figure 4 is an end elevation taken from the left of Figure 1; and

Figure 5 is an end elevation taken from the right of Figure 1.

I claim:

The ornamental design for a metering pump for chemical solutions or the like, as shown and described.

ROYAL BARTLETT SAALFRANK.
